UNITED STATES PATENT OFFICE.

JOHN R. PENNY, OF NEW SHEFFIELD, PENNSYLVANIA.

NUT-LOCK.

No. 832,998.

Specification of Letters Patent.

Patented Oct. 9, 1906.

Application filed May 17, 1906. Serial No. 317,278.

To all whom it may concern:

Be it known that I, JOHN R. PENNY, a citizen of the United States of America, residing at New Sheffield, in the county of Beaver and State of Pennsylvania, have invented certain new and useful Improvements in Nut-Locks, of which the following is a specification, reference being had therein to the accompanying drawings.

- 10 This invention relates to nut-locks; and the prime object thereof is to provide a simple device that can be readily applied to two or more bolts to prevent the nuts thereof from rotating.
- 15 Another feature of the present invention is the combination of elements by means of which not only is a nut held against movement, but the nut-holding mechanism also serves the purpose of locking the device in operative relation upon the bolt.

Devices of this character in order to be practical must not only be inexpensive to construct, but of a strong and durable nature, and it is of the utmost importance that the structure be such as will permit of easy and rapid application to bolts, for the reason that time, as a general rule, is of greater value than the lock itself.

It is the principal object of the present invention to provide a nut-lock that combines both of the desirable features as above pointed out. In the embodiments of the present invention, to be hereinafter described, and shown in the accompanying drawings, the preferred form of construction has been illustrated. It will be understood that such changes can be made therefrom that are within the scope of the claims hereto appended.

40 In the drawings, Figure 1 is a plan of my improved nut-lock, showing a piece of material, nuts, and bolts in connection with which it is used. Fig. 2 is a longitudinal sectional view of the same. Fig. 3 is a perspective view of the nut-lock, illustrating the manner of applying the lock to two nuts. Fig. 4 is a perspective view of a retaining-plate, and Fig. 5 is a perspective view of a locking-plate.

45 50 Similar numerals of reference designate corresponding parts in all the figures of the drawings.

The nut-lock as shown in the accompanying drawings consists of two elements—a retaining-plate and a locking-plate—which are constructed, arranged, and applied in the

following-described manner: The retaining-plate 1 is preferably rectangular in form and is provided with an elongated slot or bolt-opening 2 and outwardly-bent ends 3 3, said ends being provided with slots 4 4, employed for retaining the locking-plate in engagement with the plate 1. The longitudinally-disposed sides of the plate 1 are provided with lugs or teats 5 5, and as I preferably construct the plate of a resilient metal, as sheet metal, the lugs or teats 5 5, together with the ends 3 3 of the plate 1, can be easily bent. In combination with the retaining-plate 1 the locking-plate 6 is employed. The plate is substantially rectangular and is provided with an elongated slot or nut-opening 7, while the ends of the plate are provided with split lugs or teats 8 8. Assuming that the nuts 9 9 have not been placed upon the threaded ends of the screw-bolts 10 10, which pass through the piece of material 11, the retaining-plate 1 is placed upon the threaded ends or shanks of the bolts 10 10, and then the nuts 9 9 are rotated into engagement 80 with the retaining-plate 1 to hold the plate firmly against the piece of material 11. The locking-plate 6, which is also made of a resilient piece of material, is designed to fit over the nuts 9 9, and in order that it may be 85 placed in engagement with said nuts the plate is bent, (see Fig. 3,) whereby the split lugs or teats 8 8 may be inserted in the slots 4 4 of the bent ends 3 3 of the plate 1. The nut-opening 7 of the plate 6 is adapted to receive 90 the nuts 9 9 and prevent the nuts from rotating, the flat faces of the nuts lying parallel with the longitudinal edges of the nut-opening 7. The split lugs or teats 8 8 are then bent, as at 12, to prevent the locking-plate 6 95 from becoming accidentally detached from the retaining-plate 1 or the nuts 9 9; but to further insure its positive engagement with said nuts the lugs or teats 5 5 are bent upwardly to embrace the longitudinal outer 100 edges of the locking-plate 6.

It will thus be seen that an exceedingly simple construction has been devised, which may be stamped out of sheet metal and can be readily applied to two or more bolts to 105 firmly lock the nuts mounted upon said bolts thereon. It will be observed that the retaining-plate not only locks the locking-plate against relative movement, but it prevents any longitudinal play of said plate 110 upon the nuts, and thus prevents the nuts from rotating.

2
From the foregoing it is thought that the construction, operation, and many advantages of the herein-described invention will be apparent to those skilled in the art without further description, and such changes in the size, shape, proportion, and minor details of construction as are permissible by the appended claims may be resorted to without departing from the spirit and scope of the invention.

What I claim, and desire to secure by Letters Patent, is—

1. In a nut-lock, the combination with bolts and nuts, of a retaining-plate adapted to fit upon the ends of said bolts, said plate having its ends bent and slotted, lugs or teats carried by the longitudinally-disposed edges of said plate, a yielding locking-plate adapted to engage two sides of each nut, 20 split lugs carried by said locking-plate and adapted to engage in the slotted bent ends of

said retaining-plate, substantially as described.

2. A nut-lock comprising a longitudinally-slotted retaining-plate having outwardly-bent slotted ends, a yielding locking-plate adapted to be sprung into position between the ends of the retaining-plate and having lugs on its ends to engage in the slots of said outwardly-bent ends of the retaining-plate, 25 and lugs on the marginal edges of the retaining-plate for engagement with the locking-plate, in combination with bolts projecting through the slot in the retaining-plate, and nuts on said bolts received in the slot of said locking-plate. 30

In testimony whereof I affix my signature in the presence of two witnesses.

JOHN R. PENNY.
